UNITED STATES PATENT OFFICE

2,468,996

COMPENSATED THERMAL MOTOR

Ray G. Olson, Glenview, Ill., assignor to The Magnavox Company, Fort Wayne, Ind., a corporation of Delaware

Application April 14, 1947, Serial No. 741,240

7 Claims. (Cl. 172—126)

1

The present invention relates to an arrangement for automatically eliminating the undesired effects of voltage or heating-current variations in electric heaters, specifically in the heating elements of bimetallic devices.

In the copending patent application of John C. Koonz, entitled "Bimetallic variable speed timer," Serial No. 733,441, filed in the United States Patent Office on March 8, 1947, and assigned to the same assignee as the present invention and application, there is shown a timer comprising a bimetallic device, the periodic mechanical pulsations of which actuate a ratchet-and-pawl mechanism controlling cam switches or the like. If the heating current supply for such a device, or any bimetallic device for performing a timing function, is not regulated, then it is desirable to provide some arrangement for eliminating the undesired effects of heating-current variations in the heating element or elements of the bimetallic device. Undesired average current increases tend to "speed up" the operation of the timer shown in that application, for example. Conversely, undesired decreases produce a retarding effect.

It is the primary object of the present invention to provide a compensator which automatically prevents, diminishes or compensates for the undesired effects of heating-current variations in the heating elements of bimetallic devices.

Other advantages and capabilities of the invention will become apparent as the following description proceeds. In the drawings there is shown a bimetallic variable speed timer including a preferred form of compensating device in accordance with the invention. Fig. 1 is a schematic and perspective view thereof; and Figs. 2, 3 and 4 are sectional views taken on lines 2—2 of Fig. 1, 3—3 of Fig. 2 and 4—4 of Fig. 2, respectively.

For a detailed description of the timer per se, reference is made to the above-mentioned copending application of John C. Koonz. It consists essentially of a bimetallic impulsing device comprising element 11, a ratchet-and-pawl mechanism 13 actuated by the impulsing device, and a plurality of cam switches 14, 15, 16 controlled by cams 17, 18, 19 rotatably carried by a shaft 20. The impulsing is mounted in slots on posts 21, 22, secured to insulating base 23. The cam switches are sequentially closed as shaft 20 rotates. The shaft is intermittently turned by pawl 24, successively engaging teeth on ratchet wheel 25. The pawl is pivotally mounted on a bifurcated pawl mounting 26, secured to the bimetallic impulsing 11. As the impulsing element is heated, it snaps from the normal position shown in full lines to

2

that shown in dashed lines in Fig. 2, pushing pawl 24 upwardly and turning wheel 25 by one tooth. As the impulsing element cools, it snaps back to its normal position.

5 A dished member 11, initially and integrally formed of layers of suitable thermo-acting dissimilar materials and generally referred to as a bimetallic element 11 is provided.

The result is that the switches 14, 15, 16 are 10 closed at intervals dependent on the rate of generation of impulses by bimetallic element 11. This, in turn, depends on the voltage applied to the heater. It will be seen that best operation is obtained when the voltage supply is stabilized or 15 regulated.

The impulsing is so arranged that when the element 11, snaps from the full-line position to the dashed-line position the heater is disconnected, so that the element then cools.

20 It will be seen that the desired periodicity of the action of impulsing 11 would be adversely affected by undesired heating-current variations. In accordance with the invention there is provided a voltage compensating device for preventing such undesired effects.

25 It comprises means responsive to undesired current increases for automatically increasing the distance between the bimetallic element 11 and the heating elements 29, 30 during the heating cycle. This means is 30 also responsive to undesired current decreases for automatically decreasing the distance between the bimetallic element 11 and the heating elements 29, 30 during the heating cycle.

35 Specifically, heating elements 29 and 30 are mounted on insulation strips 31 and 32, which are secured by rivets 33, 34 and washers 37, 38 to a bimetallic strip 35, also initially and integrally formed of suitable thermoacting dissimilar materials such as brass and stainless steel, for 40 example. When element 35 is heated element 35 bends from the normal section illustrated in full lines in Fig. 2 to some more curved section illustrated in dashed lines. The amount of this increase in curvature depends on the average 45 amount of current flowing in heater 29, 30, i. e., on the heat generated by the heater.

When element 35, disposed in convex relation to element 11, bends away from a normal section, the distance between heater 29, 30 and bimetallic element 11 is increased by an amount functionally related to the excess of the amount of current flowing in heater 29, 30 over the normal amount flowing when the normal section is maintained.

Conversely, when the amount of current flowing in the heater is below the normal value, bi-

metallic strip 33 becomes less concave than normal relative to bimetallic element 11 and the distance between the heater and bimetallic element 11 is decreased.

The result is that undesired voltage or current increments, which cause more heat to be generated by heater 29, 30, also cause the heater to be moved away from element 11, thereby decreasing the amount of that heat actually applied to element 11, whereby the undesired effects of voltage or current increments are neutralized, compensated for or minimized. Conversely, undesired current or voltage decreases, which cause less heat to be generated by heater 29, 30 also cause the heater to be moved toward element 11, whereby increasing the amount of that heat actually applied to element 11, whereby the undesired effects of voltage or current decreases are neutralized, compensated for or minimized.

It will be understood that my invention is not limited to the particular application shown but is of general utility wherever it is desired to neutralize or compensate for undesired voltage or current deviations in electric heaters.

Integral screw-threaded extension 39 of pawl-mounting 28 projects through an aperture in bimetallic device 11, a washer 40, washers 41 and 42 to a lock nut 43. The displaceable portions of element 11, pawl 24, pawl-mounting 28, extension 39, compensator 35, washers 41, 42 and lock nut 43 are thus rigidly secured in assembly whereby they move upwardly and downwardly in unison. Insulating strips 32 and 31 overlie strip 35, whereby heater elements 29, 30 are mounted for unobstructed movement toward or away from element 11.

The electrical circuit for heater 29, 30 begins at binding post 45 on base 23 and proceeds through flexible lead 48, terminal 47 on strip 32, heater element or resistor 30, conductor 48, heater element or resistor 29, terminal 49 on strip 32, flexible lead 50, extension 39, lock nut 43, fixed contact 51, and binding post 52 on base 23. Posts 45 and 52 are coupled to a suitable source of heating current (not shown).

When element 11 snaps from the full-line position illustrated in Fig. 2 to the dashed-line position, nut 43 is separated from contact 51, breaking the electrical circuit and permitting elements 11 and 35 to cool. When element 11 cools it snaps back to its normal position, whereby the electrical circuit is again closed at 43, 51 and the cycle is repeated. When strip 35 cools it bends back to its normal position.

Thus, there is provided a simple, inexpensive, reliable arrangement for automatically eliminating the undesired effects of voltage or heating current variations in electrical heaters. This device is of particular utility when the heater is employed to furnish energy to a bimetallic impulsive device or timer.

While there have been shown and described what are at present considered to be the preferred embodiments of the present invention, it will be obvious to those skilled in the art that various modifications and substitutions of equivalents may be made without departing from the teachings of the invention and the proper scope thereof and it is accordingly intended in the appended claims to cover all such changes and modifications as fall within the true scope of the invention and outside of the scope of the prior art.

Having thus described my invention, I claim:

1. A thermally actuated timing device comprising a dish-shaped snap-impulse bimetallic operating member supported at its outer edges and adapted when heated to snap from a normal position to an inverted position and when cooled to return to normal position; a shiftable fitting at the center of said operating member and a compensating member mounted on said fitting; the compensating member comprising an auxiliary bimetallic member strip adapted to flex in one plane only and secured to the fitting at the midpoint of the strip whereby the opposite ends of the strip are unsupported and adapted to flex gradually and progressively away from the operating member in response to heat; an electrical heating unit extending between the unsupported ends of the bimetallic strip, and a pair of breaker contacts responsive to the movement of the operating member to break the circuit through the electrical heating unit.

2. A thermally actuated timing device comprising a dish-shaped snap-impulse bimetallic operating member supported at its outer edges and adapted when heated to snap from a normal position to an inverted position and when cooled to return to normal position; a shiftable fitting at the center of said operating member and a compensating member mounted on said fitting; the compensating member comprising an auxiliary bimetallic member strip adapted to flex in one plane only and secured to the fitting at the midpoint of the strip whereby the opposite ends of the strip are unsupported and adapted to flex gradually and progressively away from the operating member in response to heat; and an electrical heating unit extending between the unsupported ends of the bimetallic strip.

3. A thermally actuated timing device comprising a dish-shaped snap-impulse bimetallic operating member supported at its outer edges and adapted when heated to snap from a normal position to an inverted position and when cooled to return to normal position; a shiftable fitting at the center of said operating member and a compensating member mounted on said fitting; the compensating member comprising an auxiliary bimetallic strip adapted to flex in one plane only and secured to the fitting whereby the strip is adapted to flex gradually and progressively away from the operating member in response to heat; and an electrical heating unit supported by said bimetallic strip.

4. A thermally actuated timing device comprising a bimetallic operating member adapted when heated to move from a normal position and when cooled to return to normal position; a shiftable fitting carried by said bimetallic operating member and a compensating member mounted on said fitting; the compensating member comprising an auxiliary bimetallic member secured to the fitting adapted to flex gradually and progressively away from the operating member in response to heat; and an electrical heating unit supported by and movable with the bimetallic compensating member.

5. In a thermally actuated timing device including a bimetallic operating element, the combination of a voltage compensating device comprising a second bimetallic element oppositely oriented to the operating element but adjacent to, directly supported by, and shiftable with the operating element; together with an electrical heating unit for the operating element directly supported on and carried by said second bimetal-

lic element whereby the operating element and heating unit move in unison but are maintained in variable spaced relationship inversely proportional to temperature.

6. In a thermally actuated timing device including a bimetallic operating element, the combination of a voltage compensating device comprising a second bimetallic element adapted to flex independently of the flexing of the operating element, together with an electrical heating unit for the operating element shiftable in response to movement of said second bimetallic element.

7. In a thermally actuated timing device including a bimetallic operating element, the combination of a voltage compensating device comprising a second bimetallic element oppositely oriented to the operating element, together with an electrical heating unit shiftable with the second bimetallic operating element, whereby the heating unit moves away from the operating ele-

ment in response to increasing heater temperature and toward said operating element in response to decreasing heater temperature, whereby the heating unit and operating element are maintained in variable spaced relationship inversely proportional to temperature.
